SIDNEY L. BUCK, OF CORTLAND, NEW YORK.

CURTAIN-SUPPORT FOR AUTOMOBILE-DOORS.

1,309,610.

Specification of Letters Patent.

Patented July 15, 1919.

Application filed September 25, 1917. Serial No. 193,124.

To all whom it may concern:

Be it known that I, SIDNEY L. BUCK, a citizen of the United States of America, and resident of Cortland, in the county of Cortland, in the State of New York, have invented new and useful Improvements in Curtain-Supports for Automobile-Doors, of which the following, taken in connection with the accompanying drawings, is a full, clear, and exact description.

This invention relates to certain improvements in curtain supports for automobile doors for receiving and supporting a side curtain in such manner that it may be readily opened and closed with the door without detachment therefrom or any part of the body.

These doors are usually made hollow having a marginal framework of wood or other suitable material running around the upright sides and bottom thereof, to which is applied an outer covering of metal or equivalent material, while the inner side is usually covered with leather, leaving an intervening space of substantially the thickness of the framework of the door, and one of the objects of my invention is to provide an extensible curtain support of sufficient length when extended for use to project to or above the lower edge of the side quarters of the top, and at the same time capable of being compactly folded into a relatively small space between the inner and outer panels of the door and wholly between the upright end rails of the door frame, where it may be concealed when not in use.

Another object is to provide the upper edge of the door with a rail or plate hinged at one end and serving the double purpose of a cover for the opening through which the curtain support is folded and unfolded, and also for locking said support when adjusted for use in supporting the curtain.

Other objects and uses relating to specific parts of the device will be brought out in the following description.

In the drawings—

Figure 1 is a side elevation of a portion of an automobile body and top showing the upper portion of a door in section and one form of an extensible curtain support folded therein, the extended position of the curtain support being also indicated by dotted lines.

Fig. 2 is an enlarged transverse vertical sectional view through the upper portion of the door and folded curtain support, taken on line 2—2, Fig. 1.

Fig. 3 is a perspective view of a portion of the inner side of an automobile body showing the manner of securing a top rail to the upper portion of the door, the folding section of said rail being closed to conceal and protect the underlying curtain support which is folded within the space between the inner and outer panels of the door and between the end walls thereof.

Fig. 4 is a longitudinal sectional view through the upper portion of the door, taken on line 4—4, Fig. 3, and showing another form of curtain support in its folded or inclosed position, said support being shown by dotted lines as extended for use.

Fig. 5 is a transverse vertical sectional view through the upper portion of the door and curtain support taken on line 5—5, Fig. 4.

In Fig. 1, I have shown a portion of a body —A— of an automobile having a top —B— supported by the usual bows or braces —b—, said body being also provided with a door —C— consisting of a frame —c— and outer and inner panels —d— and —d'— which may be secured in any suitable manner to the adjacent sides of the frame —c— to form an intervening space or chamber —D— for the reception and concealment of the curtain support, presently described.

The chamber —D— is preferably closed at the top by a rail —1— having a longitudinally extending pendent flange —2— and a movable top section —3—, all of which are preferably made of sheet metal, the ends of the top of the rail and pendent flange —2— being suitably secured to the corresponding faces of the door frame —c—, while the movable section —3— is provided at one end with a pendent lug or ear —4— hinged at —5— to the flange —2— to permit the section —3— to rock vertically about the axis of said pivot in substantially the same plane as the door and from a horizontal position to at least a vertical position or farther if desired.

The movable rail section —3— extends entirely across the upper end of the chamber —D— so as to rest upon the upper edges of

the outer panel —d— and flange —2—, the latter being preferably secured to the outer edges or faces of the frame —e—.

The length of the movable rail section 5 —3— is nearly equal to that of the chamber —D— so as to allow sufficient space for the folding and unfolding of the curtain support into and out of said chamber when the section —3— is opened.

- 10 The door is preferably hinged at its rear edge in any well-known manner to the body —A— while the lid or movable rail section —3— is also hinged at or near the rear edge of the door and is provided near its 15 front end with spaced clamping members —6— and —7— for frictionally engaging the outer and inner faces of the upper portion of the flange —2— to hold said lid in its closed position against vibration or rattling, the lower edge of the inner clamping member —7— being deflected inwardly at 20 —8— to engage and frictionally retain a portion of the curtain support against undue vibration or rattling when folded into the 25 chamber —D—.

The free end, in this instance the front end, of the movable rail section or lid —3— and also the adjacent edge of the rigid top portion of the rail are provided with registering recesses —9— opening into the chamber —D— for receiving a portion of the curtain support and locking the same in its adjusted position against lateral or forward and rearward movement, as will be herein- 30 after more fully described.

The curtain support shown in Figs. 1 and 2 comprises two bars —10— and —11— of substantially the same length, nearly equal to, but slightly less than that of the chamber 40 —D—, and hinged together at one end by a pivotal bolt or rivet —12— so that the section —11— may swing freely about the axis of the pivot through an arc of approximately 180° to form a continuation of the bar —10—, or to be folded along one side thereof substantially parallel therewith, and is provided at its free end with a button —13— or other suitable fastening device to which a curtain may be attached when the 45 support is extended for use.

The front end of the bar —10— is preferably curved away from the folded bar —11— and is hinged at —14— to the adjacent end of the flange —2— near the lower 55 edge and adjacent the inner face thereof, so as to swing vertically about an axis parallel with that of the pivot —12—, or in a plane substantially parallel with that of the door.

That is, these two bars —10— and —11— 60 constitute what may be termed an extensible or jointed curtain support foldable to a substantially horizontal position wholly within the upper portion of the chamber —D— between the lid or cover plate —3— and 65 lower edge of the flange —2—, as shown by

full lines in Figs. 1 and 2, or may be extended or unfolded to a substantially vertical position, as shown by dotted lines in Fig. 1, in which latter position it is adapted to receive and support one edge of a side 70 curtain —E— indicated by dotted lines in the same figure, the other edge of the curtain at the hinged or rear edge of the door being attached in the usual manner to the supporting bows or sockets for the 75 top —B—.

The recesses —9— are made to conform to the cross sectional contour of the portion of the bar —10— which they are adapted to receive and are also positioned to register with said bar when the curtain support is adjusted for use, as shown by dotted lines in Fig. 1, and, therefore, the end walls of the recesses which are in a plane some distance above the pivotal support —14— serve 80 to lock the curtain support in its extended or upright position against forward, rearward and lateral movements.

I prefer, however, to provide additional locking means for holding the curtain support in its extended position, and for this purpose is shown a locking bar —15— extending lengthwise of and within the chamber —D— substantially the full length of the folded bars —10— and —11— and having its rear end pivoted at —16— to the flange —2— and its front end provided with a lengthwise slot —17— terminating in an upwardly extending branch —18— at the extreme forward end of the locking 95 bar —15—.

The bar —10— of the curtain support is provided with a pin or stud —19— a distance from the pivot less than the distance between said pivot and under side of the lid 105 —3— when closed and projecting into the slot —17—, so that when the curtain support is unfolded or adjusted for use, the pin —19— will ride along the slot —17— until it is registered with the branch —18—, 110 whereupon the weight of the free end of the bar —15— will cause the pin —19— to enter the offset —18— and thereby additionally lock the curtain support in its extended position.

The front end of the locking bar —15— terminates within the front edge of the lid —3— and when the curtain support is adjusted for use, this end of the bar is brought closer to the under side of said lid so that 120 in order to release the locking bar from its holding position preparatory to refolding the curtain support within the upper portion of the chamber —D—, it is simply necessary to rock the lid upwardly and rearwardly, whereupon the operator may readily insert the finger in the upper open side of the chamber and engage and lift the free end of the locking bar sufficiently to disengage the branch —18— from the pin 125 —19—.

19 thereby allowing the curtain support to be rocked rearwardly and downwardly, causing the pin 19 to ride rearwardly along the slot 17 until both bars 10 and 11 have been folded beneath the upper edge of the door, at which time the lid may be returned to its closed position and frictionally locked in place by the clamping members 6 and 7, as previously explained.

When the curtain support is thus folded, its upper bar 11 lies close to the under side of the lid and also close to the inner face of the flange 2 with respect to the chamber D, the face of the bar 11 adjacent the clamping member 7 being of convex cross section so as to allow the inwardly deflected portion 8 of said clamping member to ride against and across said convex face, thereby placing the bar 11 under slight tension to coöperate with the clamping member 7 in frictionally holding said bar and lid against relative vibration.

That is, this frictional engagement between the bar 11 and clamping member 7 not only causes the folded curtain support as a whole to hold the lid in its closed position, but also enables the closed lid to hold the curtain support in its folded position, the end edges of the lid and adjacent edges of the relatively stationary portions of the top rail which they engage being preferably beveled in upwardly diverging planes to additionally support the lid against sagging, and at the same time affording a straight, smooth finish along the upper edge of the door.

The axis of the pivot 12 connecting the bars 10 and 11 is substantially coincident with the adjacent edges of said bars when folded one upon the other, the adjacent ends of said bars being provided with stop shoulders 20 at right angles thereto and radial to the axis of the pivot 12 at one side thereof to limit the opening movement of the bars to a substantially straight vertical line.

When the bars are in this unfolded position, the stop shoulders 20 are at the rear side of the pivot, while the curtain supporting stud or button 13 is preferably secured to the upper end of the uppermost bar 11, so that the tension of the curtain when attached to the bows or sockets at the rear of the door serves to hold the stop shoulders in engagement and to prevent flexing of the joint aided by the end walls of the recesses 9 which hold the lower section 10 in an upright position.

It is now evident that when the curtain support is adjusted for use and the curtain attached thereto in the manner just described, the door with the curtain thereon may be opened and closed to allow free

entrance and entry of the passengers without displacing any portion of the door curtain from its supporting means.

When it is desired to dispense with the curtain, it may be readily detached from its supports, whereupon the lid 3 may be rocked upwardly and rearwardly to its open position, the locking member 15 released in the manner described, and the bars 10 and 11 folded downwardly within the chamber D, after which the lid may be closed, thereby concealing the curtain support, and at the same time giving the door its usual finished appearance with the rail across the top thereof.

In Figs. 3, 4 and 5, the door and top rail, including the hinge section or lid 3 are substantially the same as those shown in Figs. 1 and 2, previously described, the curtain-supporting bars 10 and 11 being also similar to those shown in Figs. 1 and 2, except that they are provided with folding branches 10' and 11' and that instead of providing the locking bar 15, I have provided a modified locking means consisting of folding members 21 and 22 hinged together at one end at 23 and having their opposite ends hinged, respectively, to the bar 10 at 24 and to the flange 2 at 25, thus producing what may be termed a toggle connection and toggle lock between the curtain support and flange 2.

The toggle arms 21 and 22 are arranged to fold one upon the other beneath the bar 10 when the latter is folded within the chamber D and also to unfold in substantially a straight line when the bars 10 are adjusted for use, the connections between the toggle arms and flange 2 permitting said arms to fold and unfold wholly within the space between the closed lid 3 and lower edge of the flange 2, as shown more clearly in Fig. 4.

The adjacent ends of the toggle arms 21 and 22 are provided with stop shoulders 26 at right angles thereto and radial to the pivot 23 to limit the unfolding flexing action of said arms to a substantially straight line for automatically locking the curtain support in its extended position.

This toggle lock may be readily released by hand through the open upper side of the chamber D when the lid 3 is open to allow the curtain support to be folded within said chamber to the position shown by full lines in Fig. 4.

The purpose of the branch arms 10' and 11' is to permit the use of a curtain considerably wider than the door or one which will extend forwardly some distance beyond the corresponding free edge.

of the door, and in order that they may occupy a minimum space when folded, they are preferably made U-shape in cross section to fit across the top and around the 5 sides of their respective bars —10— and —11—.

The branch arm, —10'— is pivoted at one end at —27— to the bar —10— and is provided with a stop shoulder —28— co-operating with one edge of said bar to limit its opening movement to a position at substantially right angles thereto, the opposite end of the bar being provided with a button —13— or equivalent device for attachment 10 of a curtain thereto.

The other arm, —11'— is pivoted at one end at —30— to the free end of the bar —11— and is also provided with a shoulder —31— co-operating with one edge of said 20 bar to limit its opening movement to a position at substantially right angles thereto, in the same direction as and substantially parallel with the other arm —10'— when the curtain support is extended for 25 use, as shown by dotted lines in Fig. 4, the other end of the arm —11'— being provided with a button —13— or equivalent means for attaching a curtain thereto.

These branch arms —10'— and —11'— 30 when adjusted for use extend forwardly some distance beyond the free edge of the door and are preferably of approximately the same length, the corresponding edge of the curtain being, therefore, extended some 35 distance beyond the arms —10— and —11—, and attached to the buttons —13—.

It will be observed upon reference to Fig. 2 that the branch arm —10'— is adapted to swing through an arc of substantially 40 90°, while the branch arm —11'— is adapted to swing through an arc of substantially 270°, thus permitting both arms to fold over and upon the upper edges of their respective arms —10— and —11— when the 45 latter are folded within the chamber —D—.

Aside from the modified form of locking device and branch arms —10'— and —11'—, the construction and operation of the device shown in Figs. 3, 4 and 5 is substantially 50 the same as previously described for the construction shown in Figs. 1 and 2, and while I have referred to the door as hinged at its rear end and to the curtain support as hinged to the door near its front end and 55 the lid —3— as hinged near the rear end of the door, such description only applies to the construction shown, and it is evident that the hinging of the door may be reversed, as it is evident that the direction of opening 60 of the door is immaterial so long as the curtain support is hinged upon the free edge of the door and the lid hinged to the hinged end of the door.

It is also evident that certain changes 65 might be made in the construction and oper-

ation of the several parts of the curtain support and lid without departing from the spirit of my invention.

What I claim is:

1. In combination with a vehicle door 70 having a chamber open at the top, and a lid normally covering the opening, a curtain support hinged to the door within said chamber and composed of bar sections hinged together end to end to fold and unfold into 75 and out of said chamber when the lid is open, and a locking bar hinged to the door within said chamber and co-operating with one of the first named bars to lock the curtain support in its unfolded position. 80

2. In combination with a vehicle door having a chamber open at the top, and a lid normally covering the opening, a curtain support hinged to the door within said chamber and composed of bar sections hinged 85 together end to end to fold and unfold into and out of said chamber when the lid is open, and a locking bar hinged to the door within said chamber and co-operating with one of the first named bars to lock the curtain support in its unfolded position, said lid co-operating with the unfolded curtain support for additionally locking it against folding when the lid is closed. 90

3. In combination with a vehicle door 95 having a chamber open at the top, and a lid normally covering the opening, a curtain support hinged to the door within said chamber and composed of bar sections hinged together end to end to fold and unfold into 100 and out of said chamber when the lid is open, and a locking bar hinged to the door within said chamber and co-operating with one of the first named bars to lock the curtain support in its unfolded position, and a clamping member on the lid frictionally engaging 105 one of the first named bars when the lid is closed to hold said bars in their folded position against rattling.

4. In combination with a vehicle door 110 hinged along one of its upright edges and provided with a lengthwise chamber open at the top, a lid for the opening, a curtain support composed of bars hinged together end to end to fold one upon the other and to unfold in a substantially straight line, one of the bars being hinged to the door near the free edge thereof and within the chamber to swing lengthwise thereof from a substantially horizontal position within the chamber 115 to a substantially vertical position near the free edge of the door when the lid is open, said lid having means for engaging the first named arm and holding the curtain support in its vertical position when the lid is closed. 120

5. In combination with a vehicle door hinged along one of its upright edges and provided with a lengthwise chamber open at the top, a lid for the opening, a curtain sup- 130

port composed of bars hinged together end to end to fold one upon the other and to unfold in a substantially straight line, one of the bars being hinged to the door near the free edge thereof and within the chamber to swing lengthwise thereof from a substantially horizontal position within the chamber to a substantially vertical position near the free edge of the door when the lid is open, said lid having means for engaging the first named arm and holding the curtain support in its vertical position when the lid

is closed, each of said bars being provided with a branch hinged thereto to fold and unfold from a position substantially parallel therewith to a position at substantially right angles thereto.

In witness whereof I have hereunto set my hand this 12th day of September, 1917.
